(57) CLAIM

The ornamental design for a skateboard, as shown and described.

DESCRIPTION

FIG. 1 is a front perspective view of a skateboard of the new design;

FIG. 2 is a rear view thereof;

FIG. 3 is a front view thereof;

FIG. 4 is a right-side view thereof;

FIG. 5 is a left-side view thereof;

FIG. 6 is a top view thereof;

FIG. 7 is a bottom view thereof;

FIG. 8 is an enlarged front perspective partial view taken from the front truck (right side) of FIG. 1, the opposite side being a mirror image;

FIG. 9 is an enlarged front perspective partial view taken from the rear truck (left side) in FIG. 1, the opposite side being a minor image; and,

FIG. 10 is an enlarged bottom perspective partial view taken from the rear truck (left side) in FIG. 7, the opposite side being a mirror image.

The broken lines shown are included for the purposes of illustrating the unclaimed portions of the article and form no part of the claimed design.
